**FORMULATION FOR A BIO BASED 99%
NATURAL CLEANSER FOR AN AUTOCLAVE
UNIT**

FIELD OF THE INVENTION

The present invention relates to novel a cleaning formulation having a unique combination of natural bio based ingredients to provide a natural and optimum cleanser for autoclave units.

BACKGROUND OF THE INVENTION

Presently existing cleansers do not meet the goal of providing a natural cleanser using natural bio based ingredients, which is a 99% bio based natural cleanser for an autoclave unit. The present invention meets this goal since the natural ingredients provide a unique combination of natural ingredients, and the quantities of the ingredients are also novel.

OBJECTS OF THE INVENTION

It is an object of the present invention to provide a 99% natural bio based cleanser having a unique combination of natural ingredients and a novel combination of quantities of each ingredient, which provide an optimum cleanser using natural ingredients.

SUMMARY OF THE INVENTION

The present invention provides a natural 99% bio based cleanser having the following unique combination of ingredients and quantities for cleaning an autoclave unit. The ingredients are:

Natural Citric Acid in Powder Form (50 pounds), which is at least 15% by volume.

High Purity Deionized Water (38 gallons), which is at least 60% by volume.

Natural Lemon Juice (1 to 1½ gallons added to the Deionized Water), which is at least 1% by volume.

Dried Cloves (1 to 3 ounces added to the Deionized Water), which is at least 1% by volume.

Dried Ground Garlic (1 to 3 ounces added to the Deionized Water), which is at least 1% by volume.

Dried Peppermint Leaves (1 to 3 ounces added to the Deionized Water), which is at least 1% by volume.

Dried Thyme Leaves (1 to 3 ounces added to the Deionized Water), which is at least 1% by volume.

Dried Cinnamon (1 to 3 ounces added to the Deionized Water), which is at least 1% by volume.

Dried Pimento Leaves (1 to 3 ounces added to the Deionized Water), which is at least 1% by volume.

Bio Detergent Powder made of Natural Soap (5 gallons to 10 gallons added to the Deionized Water), which is at least 10% by volume.

Total—50 gallons

**DETAILED DESCRIPTION OF THE
PREFERRED EMBODIMENT**

The present invention provides the following unique combination of ingredients and quantities for cleaning an autoclave.

2

Autoclave Cleanser (50 Gallons)

This is an organic and natural liquid cleanser that is 99% bio based for cleaning an autoclave. The ingredients are:

5 Natural Citric Acid in Powder Form (50 pounds), which is at least 15% by volume.

High Purity Deionized Water (38 gallons), which is at least 60% by volume.

Natural Lemon Juice (1 to 1½ gallons added to the Deionized Water), which is at least 1% by volume.

Dried Cloves (1 to 3 ounces added to the Deionized Water), which is at least 1% by volume.

Dried Ground Garlic (1 to 3 ounces added to the Deionized Water), which is at least 1% by volume.

Dried Peppermint Leaves (1 to 3 ounces added to the Deionized Water), which is at least 1% by volume.

Dried Thyme Leaves (1 to 3 ounces added to the Deionized Water), which is at least 1% by volume.

Dried Cinnamon (1 to 3 ounces added to the Deionized Water), which is at least 1% by volume.

Dried Pimento Leaves (1 to 3 ounces added to the Deionized Water), which is at least 1% by volume.

Bio Detergent Powder made of Natural Soap (5 gallons to 10 gallons added to the Deionized Water), which is at least 10% by volume.

Total—50 gallons.

ADVANTAGES OF THE PRESENT INVENTION

It is an advantage of the present invention to provide a unique combination of natural bio based ingredients and a unique combination of quantities of each ingredient, which provide an optimum cleanser, using natural ingredients.

A latitude of modification, change and substitution is intended in the foregoing disclosure, and in some instances, some features of the invention will be employed without a corresponding use of other features. Accordingly, it is appropriate that the appended claims be construed broadly and in a manner consistent with the spirit and scope of the invention herein.

What is claimed is:

1. A bio based 99% natural cleanser for an autoclave unit, comprising:

(a) natural citric acid in powder form of 50 pounds, which is about 15% by volume;

(b) high purity deionized water having 38 gallons, which is at least 60% by volume;

(c) Natural Lemon Juice (1 to 1½ gallons added to the Deionized Water), which is at least 1% by volume;

(d) Dried Cloves (1 to 3 ounces added to the Deionized Water), which is at least 1% by volume;

(e) Dried Ground Garlic (1 to 3 ounces added to the Deionized Water), which is at least 1% by volume;

(f) Dried Peppermint Leaves (1 to 3 ounces added to the Deionized Water), which is at least 1% by volume;

(g) Dried Thyme Leaves (1 to 3 ounces added to the Deionized Water), which is at least 1% by volume;

(h) Dried Cinnamon (1 to 3 ounces added to the Deionized Water), which is at least 1% by volume;

(i) Dried Pimento Leaves (1 to 3 ounces added to the Deionized Water), which is at least 1% by volume;

(j) Bio Detergent Powder made of Natural Soap (5 gallons to 10 gallons added to the Deionized Water), which is at least 10% by volume.
